UNITED STATES PATENT OFFICE.

ARDEN L. HAMILTON, OF BROOKLYN, NEW YORK.

INNER RING FOR PISTONS.

Application filed March 9, 1925. Serial No. 13,953.

To all whom it may concern:

Be it known that I, ARDEN L. HAMILTON, a citizen of the United States, residing at Brooklyn, county of Kings, and State of New York, have invented a certain new and useful Inner Ring for Pistons, of which the following is a specification.

This invention relates to inner ring adapted to be used in conjunction with the piston rings of internal combustion engines to be positioned between the inner circumference of the rings and the bases of the associated piston grooves. The purpose of an inner ring is to centralize the piston with respect to the cylinder wall to prevent lateral play of the piston commonly known as piston slap. When a piston has lateral play or slap, it will tilt and the piston rings will fail to present a proper wiping edge to the cylinder wall. This defect, inevitable in worn pistons, is frequently the cause of oil and carbon troubles. Inner rings when associated with a loose piston greatly obviate these disadvantages.

Inner rings are, in their most convenient form, manufactured in long strips of spring steel, of a width slightly less than the width of the piston groove and such strip material is crimped or bent at spaced distances longitudinally so that its length is made up of a succession of substantially straight portions united by relatively short bends. The mechanic, when using the strip, cuts therefrom the lengths of material desired from time to time as occasion may require. Inasmuch as it is difficult to accurately measure the circumference of the base of the piston groove and accurately apply it to the strip material, the mechanic roughly estimates the length required and then cuts off a piece of the strip somewhat longer than necessary, thereafter proceeding to fit the strip to the piston groove by successively cutting off short lengths until the proper length is obtained.

It is the object of this invention to overcome this tiresome and slow method of fitting.

Speaking generally, the invention embodies a strip of spring steel bent to form a succession of relatively straight portions and at least one end of which strip is graduated and marked according to different piston sizes. That is to say I start at one end of the strip and mark off on the strip certain

lengths appropriate to pistons of different sizes and each graduation is marked with a designation showing the size of piston to which that particular length is appropriate, so that a mechanic may readily see where to cut the strip in order to obtain the proper length for any particular piston. This arrangement eliminates waste inherent in prior practice and enables a quick fitting through obviating loss of time.

Features of the invention, other than those specified, will be apparent from the hereinafter detailed description and claims, when read in conjunction with the accompanying drawings.

The accompanying drawings illustrate one practical embodiment of the invention, but the construction therein shown is to be understood as illustrative, only, and not as defining the limits of the invention.

Figure 1 is a perspective view showing a portion of the length of strip material embodying the present invention; and.

Figure 2 shows such material laid out flat and graduated in accordance with this invention.

In Figure 1 of the drawings, I have illustrated a length of strip material made in accordance with this invention and from this showing it will appear that the strip is bent to form a succession of straight portions 1 between which are relatively easy bends. In practice I make this strip of spring steel preferably about .015 of an inch thick and in different widths so as to fit piston grooves of different sizes.

After carefully calculating the diameter of the base of the groove for a piston of each of the commonly used sizes I next calculate the circumference of the base of each of said grooves and after having obtained these circumferential dimensions I lay off equal distances from at least one end of the strip and as shown in Figure 2 form on the strip graduations 2, 3, 4, 5, etc. by stamping, marking, printing or otherwise delineating on the strip a line or mark that can be readily seen. I next mark the strip adjacent each of these graduations with the diameter of the piston to which the length mark is appropriate. For example, the graduation 2 is marked $2\frac{1}{8}$ showing that the distance which I have designated w , if cut from the strip, will properly fit the groove of the $2\frac{1}{8}$ piston. Similarly the graduation 3 is

marked $3\frac{1}{8}$ showing that a piece equal in length to the distance y will properly fit a piston $3\frac{1}{8}$ " in diameter. I mark upon one end of the strip sufficient graduations to enable a mechanic to fit the pistons of any of the well known makes of car having piston grooves which that particular strip will properly fit.

In practice, both ends of the strip or only one end of the strip may be marked and it is frequently found convenient to mark but one end of the strip and then use this end as a scale by which the other or unmarked end of the strip may be measured. In other words, the parts to be used are cut from the unmarked end of the strip, the marked end thereof serving as a scale to show a mechanic the lengths which he needs for successive jobs. If both ends of the strip are marked the first cut may be made from the marking of one end and proceeding cuts made from the same end, while employing the scale at the other end as a gauge.

The drawings show the invention in its preferred practical form but the invention is to be understood as fully commensurate with the appended claims.

Having thus fully described the inven-

tion, what I claim as new and desire to secure by Letters Patent is:

1. Inner ring stock comprising a thin strip of resilient sheet metal, at least one end portion of which strip is provided with graduations spaced from said end of the strip distances corresponding to the circumference of the base of the piston ring grooves of pistons of different sizes, each of said graduations bearing a designation in terms of conventional piston diameters.

2. Inner ring stock comprising a strip of spring steel longitudinally crimped and provided near one end thereof with a marking designated in accordance with the piston diameter and spaced from the end of the strip a distance substantially equal to the circumference of the base of the ring groove of such piston.

3. Inner ring stock comprising a strip of spring steel longitudinally crimped and graduated longitudinally to show the length of material which must be cut from a strip to properly cooperate with a particular piston size.

In testimony whereof I have signed the foregoing specification.

ARDEN L. HAMILTON.
